UNITED STATES PATENT OFFICE.

CLARENCE M. HENDERSON, OF BERKELEY, CALIFORNIA.

WALL-BED.

1,263,889.

Specification of Letters Patent. Patented Apr. 23, 1918.

Application filed November 17, 1915. Serial No. 61,913.

To all whom it may concern:

Be it known that I, CLARENCE M. HENDERSON, a citizen of the United States, residing at Berkeley, in the county of Alameda and State of California, have invented new and useful Improvements in Wall-Beds, of which the following is a specification.

My invention relates to wall and folding beds, and is especially designed for that class 10 of beds which is reversible upon a pivot connection, when in an upturned or folded position, so that when lowered to a horizontal position the legs may rest upon the floor.

The invention consists of castings attached 15 to the floor, and others upon which the bed and door are mounted and turnable, said castings being so grooved as to interlock and hold the bed in position when it is ready to be lowered for use.

20 It also includes top and bottom turnable supports upon which the two are carried and turnable, and details of construction which will be more fully explained by reference to the accompanying drawings, in which—

Figure 1 is a front view of the head frame attached to the door.

Fig. 2 is a section through 2—2 of Fig. 1.

Fig. 3 is a perspective view of the top 30 pivot plate.

Fig. 4 is a perspective view of the top pivot socket.

Fig. 5 is a perspective view of the lower pivot socket.

35 Fig. 6 is a perspective view of the pivot floor plate.

Fig. 7 is a transverse section showing the engagement.

The bed comprises the head portion A 40 and the side rails A' which are pivoted to the head as shown at 1 so as to be raised into the vertical position shown, or extended for use by turning down at right angles with the head (not shown). The 45 top rail of the head A is secured to the vertical post 2 by a clamp 2^a and the bottom rail is supported upon the socket plate 4 (which supports the lower end of the post 2), by suitable clamps 2^b, and the bed 50 is turnable with the post and socket plate.

The plate 4 carries the socket 3 in which the lower end of the post may be supported, and the upper end of the post is also supported in a socket 11 which is secured 55 to the top of the door B at 12. The door

is supported upon a flange 4^a projecting from the plate 4 at the side opposite to the socket 3, and may be secured by screws through holes 5 in the plate 4. The turning of the bed and door to conceal the bed 60 in a closet and at the same time close the door, is effected by means of pivots which are eccentric to the line of the post and its sockets, as follows:

Below the plate 4^a is an extension pivot 65 6, which is in alinement with the top pivot plate to be hereinafter described, and is adapted to enter a socket 7 in the floor plate 8. This floor plate is properly secured in position and it has cast upon it upwardly 70 extending ribs 9. Upon the contiguous bottom 4^a are formed corresponding lugs 10, so placed that when brought into alinement with the lugs 9 they will settle over said lugs and form a detent, as plainly shown 75 in Fig. 7. It will be understood that either of these sets of lugs may form a groove into which the other ones will fit and engage when in proper alinement. When the bed is being turned between its closed and 80 open position, these lugs will ride upon each other, raising the bed slightly and forming a turning bearing; and when in alinement they will settle together and form a lock or 85 detent which will prevent the bed from turning in either direction.

The upper end of the shaft 2 is supported in a socket casting 11, which is fixed to the door by flanges 12 and screws passing through them, and this socket is in alinement with the socket 3 at the lower end; the door being practically supported out of the line of these sockets. The socket 11 has formed at the upper end and projecting therefrom a lug 13, and this lug is 90 adapted to fit and engage with a pin 14 formed on the pivot plate 15 which is secured to the top of the door casing. The pivot 14 is in alinement with the pivot 6 of the bottom plate substantially in alinement with the door, while the supporting plates of the bed are mounted to turn about in unison with the shaft 2. The door-way is adapted to double doors, one of which B forms the panel turnable with the bed, and the other C may be hinged and opened so as to provide space for the bed to turn into and out of the closet.

By this arrangement I provide turning means for the support of the bed and a pivot 110

out of alinement with said turning means about which the whole bed frame and door may be turned, and this second turning means provides a lock which will prevent irregular movements and will hold the bed in proper position after it has been either raised or lowered for use. Reversal of the structure, by turning about its vertical pivots, turns the bed into the closet and simultaneously closes that part of the door which is movable with the bed.

An important feature of my invention lies in the independent support of the door and bed so that no strain or twisting action will affect the door by reason of unbalanced weight or other action of the bed.

Another advantage in having the bed turn horizontally on a pivot with relation to the pivots of the door, is that it is possible to raise the door and turn the door slightly to disengage the lugs 9 and 10 without having to swing the whole bed.

Having thus described my invention, what I claim and desire to secure by Letters Patent is—

1. In combination, a lower and an upper plate, means for supporting said plates, a bed, a supporting plate for supporting the bed at the lower portion thereof, said lower plate being provided with a socket, a pivot pin depending from said supporting plate adapted to fit in said socket, a lug, means connecting the upper portion of the bed to said lug, said lug provided with an aperture, a pin depending from said upper plate in said aperture, said pin and said socket being in alinement so that the bed may swing on said pins as pivots, and interlocking lugs on said lower plate and said supporting plate for locking the bed in two positions into which the bed may be swung on said pivot pins.

2. In combination with a door, sockets secured to the top and bottom of said door, a post mounted in said sockets, a bed mounted on said post, a horizontal extension from one side of the lower socket upon which the door rests, a pivot pin depending from said extension, a floor plate having a socket to receive said pivot pin, an upper plate, fixed above the door, a pivot pin depending from said plate, a lug offset from said upper socket provided with an aperture to receive said pivot pin, said upper and lower pins being in alinement to allow the door and bed to turn thereon, interlocking lugs on said floor plate and said extension adapted to lock the door in open and closed positions respectively.

3. The combination with a door of sockets secured to the bottom and top of the door, a vertical post carried in said sockets, a bed having its head fixed to said post, lugs with pivots offset from the sockets, journals fixed above and below, and in line with said

pivots, and means for locking said bed and door structure against turning from the closed position.

4. In combination with a closet door, castings secured to said door, means for pivoting said castings to the door casing to enable the door to swing so as to open and close the closet, sockets formed in said castings out of alinement with the pivot axes of said castings, a post carried in said sockets, a folding bed secured to said post adapted to swing into the closet when the closet door is swung closed.

5. In combination, a door and a bed, means for supporting the door and the bed independently of each other, pivot means in the plane of the door about which said dual supporting means, door and bed, are turnable, and interengaging means for retaining said supporting means, door and bed against turning movement when swung into opposite positions, said interengaging means being adapted to be disengaged upon lifting the door.

6. In a wall bed, the combination of a reversible panel, a closet with a doorway in which the panel is turnable, brackets to which the top and bottom of the panel are centrally fixed, and having pivot pins in the plane of the panel, vertical sockets on the brackets, offset from the pivot pins and panel, a post supported in the sockets and a bed, the head of which is fixed to the post, said bed being turnable in unison with the bracket and panel, to be concealed within the closet.

7. In a wall bed, the combination of a reversible door panel, a closet with a doorway in which the panel is turnable, upper and lower brackets to which the top and bottom of the panel are centrally fixed, the lower bracket having a flange on which the panel is supported, vertical sockets upon the brackets out of line with the panel, a post supported in the sockets, a bed, the head of which is fixed to the post and turnable in unison with the brackets and panel, pivots on the brackets in line with the panel and eccentric to the post and its sockets to transfer the bed into or out of the closet, a floor plate with raised lugs in line with the pivot about which the panel is turnable, and corresponding lugs and grooves upon the panel supporting flange engageable when the bed is faced either inwardly or outwardly to retain it in position.

8. The combination with a wall bed and a closet, of a door panel centrally pivoted and turnable with either face toward the closet, brackets upon the upper and lower ends of the door panel and pivots carried thereby, the lower bracket having a flange on which the panel is supported, vertical sockets on the brackets eccentric to the door and pivots, a post having its ends fixed in the sockets,

a bed, the head of which is secured to the post parallel with the door panel, a floor plate with raised lugs in line with the pivots and parallel with the door opening, and corresponding lugs and grooves upon the panel supporting flange.

In testimony whereof I have hereunto set

my hand in the presence of two subscribing witnesses.

CLARENCE M. HENDERSON.
